UNITED STATES PATENT OFFICE.

JOHN R. STUNKARD, OF BRAZIL, ASSIGNOR TO TIMOTHY L. BOSART, OF INDIANAPOLIS, INDIANA.

MACHINE FOR MANIPULATING THE NUTS OF TIRE-BOLTS.

SPECIFICATION forming part of Letters Patent No. 439,257, dated October 28, 1890.

Application filed August 26, 1890. Serial No. 363,139. (No model.)

To all whom it may concern:

Be it known that I, JOHN R. STUNKARD, a citizen of the United States, residing at Brazil, in the county of Clay and State of Indiana, have invented certain new and useful Improvements in Machines for Manipulating the Nuts of Tire-Bolts, of which the following is a specification.

The object of my said invention is to produce a machine by which the nuts of the bolts which secure the tires to the rims of vehicle-wheels may be quickly and conveniently put in place or removed.

This invention will be first fully described, and then pointed out in the claims.

Referring to the accompanying drawings, which are made a part hereof, and on which similar letters of reference indicate similar parts, Figure 1 is a top or plan view of a machine embodying my said invention, a portion of a vehicle-wheel being also shown by means of dotted lines; Fig. 2, a side elevation of such a machine; Fig. 3, a longitudinal sectional view on the dotted line 3 3, in Fig. 1, through the machine and the wheel being operated upon; Fig. 4, a detail perspective view of the wrench and the parts immediately adjacent thereto, and Fig. 5 a transverse sectional view on the dotted line 5 5 in Fig. 2.

In said drawings, the portions marked A represent the stationary part of the framework; B, the sliding or adjustable part of the framework; C, the wrench portion of the machine; D, a crank-shaft by which said wrench portion is driven, and E a lever by which the wheel is held in proper position while the nuts to the tire-bolts are being operated upon.

The frame portion A is usually a plain bar, as shown, and should be secured fixedly upon a bench or frame in convenient position for use. It carries an upwardly-projecting stud A', which enters the hole in the hub of the wheel, and upon which said wheel is turned, bringing the nuts successively into position to be operated upon in using the machine.

The frame portion B is similar in general form to the frame portion A upon which it rests. It is secured to said frame portion A by brackets b, which extend down around the edges thereof, and which form slides by which

the two frame portions are adjustably secured together. It is provided with the several bearings B', B², and B³, in which the wrench-shaft and the crank-shaft are mounted. It also has a bearing B⁴, in which the lower end of the lever E is pivoted.

The wrench C is a socket-wrench, and its shaft C' rests in bearings in the upper ends of the bearing-blocks B' and B². It is separable from its shaft, and by simply providing several of these wrench portions of different sizes and exchanging one for another, as occasion may require, the same machine may be used for manipulating the nuts of different-sized bolts. The socket in the wrench extends back some distance beyond its point, and openings extend out from the bottom of the socket through the sides of sufficient size to permit nuts of the size which the wrench is adapted to operate to pass through. This enables the person operating the machine to remove a series of nuts without stopping to take the nuts out of the wrench, as said nuts will simply be forced back to the bottom of the socket by succeeding nuts and drop out of these holes to the floor or into a convenient receptacle provided to receive them.

The crank-shaft D is an ordinary crank-shaft mounted in bearings in the bearing-blocks B', B², and B³, and has an ordinary hand-crank D', mounted on its outer end, by which it is driven. Near its inner end, between the bearing-blocks B' and B², it is provided with a spur-pinion D², which engages with a similar spur-pinion C² on the wrench-shaft C', and thus drives said wrench-shaft and the wrench.

The lever E is pivoted at its lower end by a pivot e to the bearing-block B⁴, and extends up past the rim of the wheel when the machine is in operation, and is adapted to be held against the rim of said wheel, thus holding the nut being operated on firmly into engagement with the wrench. It is provided with a cross-arm or projecting portion E', which is adapted to extend out a short distance on each side over the side of the rim of the wheel, thus holding said wheel in parallel relation to the frame of the machine, as well as in close relation with the wrench mechan-

ism. Said cross-arm E' is preferably curved, as shown, to correspond to the curvature of the wheel-rim.

Having thus fully described my said invention, what I claim as new, and desire to secure by Letters Patent, is—

1. The combination, in a machine for manipulating the nuts of tire-bolts, of two frame portions, one of which carries a stud for the wheel-hub and the other of which carries the mechanism for turning the nut, the two portions being adjustable one upon the other, substantially as set forth.

2. The combination, in a machine for manipulating the nuts of tire-bolts, of a frame having a stud for the hub of the wheel, mechanism for turning the nut, and a lever whereby the rim of the wheel may be held into close relation with said mechanism, substantially as set forth.

3. The combination, in a machine for manipulating the nuts of tire-bolts, of a wrench-shaft, a socket-wrench mounted thereon and provided with a deep socket having holes extended out through its sides at the bottom, and mechanism for operating the same.

4. The combination, with mechanism for manipulating the nuts of tire-bolts, of a pivoted lever secured to the same frame as said mechanism and provided with a cross-arm adapted to extend out over the side of the

wheel-rim and hold said wheel-rim into parallel relation with the frame, substantially as set forth.

5. The combination, in a machine for manipulating the nuts of tire-bolts, of two frame portions adjustable in relation to each other, a stud for the wheel-hub upon one of said frame portions, and mechanism for manipulating the nut upon the other frame portion consisting of a wrench-shaft, a socket-wrench on said shaft, a crank-shaft gearing connecting said two shafts, and a crank upon said crank-shaft, substantially as set forth.

6. The combination of the two frame portions A and B, adjustable relatively to each other, the shafts C' and D, mounted in bearings on the frame part B and geared together, a socket-wrench on said shaft C', a crank on said shaft D, and a lever E for holding the wheel-rim against the wrench, the whole forming a machine for manipulating the nuts of tire-bolts, substantially as shown and described.

In witness whereof I have hereunto set my hand and seal, at Brazil, Indiana, this 14th day of August, A. D. 1890.

JOHN R. STUNKARD. [L. S.]
